UNITED STATES PATENT OFFICE.

LOUIS P. WHITEMAN, OF NEW YORK, N. Y.

DESIGN FOR A BICYCLE-LAMP.

SPECIFICATION forming part of Design No. 26,736, dated March 9, 1897.

Application filed January 29, 1897. Serial No. 621,245. Term of patent 7 years.

To all whom it may concern:

Be it known that I, LOUIS P. WHITEMAN, a citizen of the United States, and a resident of the city of New York, in the county and State of New York, have invented and produced a new and original Design for a Lamp, of which the following is a specification, reference being had to the accompanying drawing, forming part thereof, and in which is illustrated a side elevation of a lamp incorporating my design.

The leading feature of my design consists of the form and configuration of the lamp, substantially as illustrated in the accompanying drawing.

In the drawing, A denotes the vertical cylindrical body of the lamp; B, the cap on said

body; D, the base and oil-fount for said body; E, the lens at the front of said body; F, the mounting for the lens, and G the jewel side 20 light for the body A. The cap B and base D are of ornamental form, as shown, and the parts of the lamp form a harmonious whole of ornate appearance.

What I claim is—

The design for a lamp, substantially as shown and described.

Signed at New York, in the county and State of New York, this 27th day of January, 1897.

LOUIS P. WHITEMAN.

Witnesses:

CHAS. C. GILL,
E. JOS. BELKNAP.
